R. C. HUFF,
FEEDING DEVICE FOR LIQUID FUEL.
APPLICATION FILED NOV. 27, 1920.

1,399,964.

Patented Dec. 13, 1921.

Inventor
Russell C. Hugg.

By Watson E. Coleman

Attorney:

UNITED STATES PATENT OFFICE.

RUSSELL C. HUFF, OF ELDORADO, KANSAS.

FEEDING DEVICE FOR LIQUID FUEL.

1,399,964.

Specification of Letters Patent. Patented Dec. 13, 1921.

Application filed November 27, 1920. Serial No. 426,870.

To all whom it may concern:

Be it known that I, RUSSELL C. HUFF, a citizen of the United States, residing at Eldorado, in the county of Butler and State 5 of Kansas, have invented certain new and useful Improvements in Feeding Devices for Liquid Fuel, of which the following is a specification, reference being had to the accompanying drawings.

10 This invention relates to certain improvements in feeding devices for liquid fuel, and it is an object of the invention to provide a novel and improved device of this general character whereby the supply of fuel to the carburetor of an internal combustion engine 15 is effectually controlled.

Another object of the invention is to provide a novel and improved device of this general character whereby the control of the 20 feed is effected through the instrumentality of a vacuum tank, and wherein said tank is provided with a vent opening to facilitate the desired operation of the device.

The invention consists in the details of 25 construction and in the combination and arrangement of the several parts of my improved feeding device for liquid fuel whereby certain important advantages are attained and the device rendered simpler, less 30 expensive and otherwise more convenient and advantages for use, as will be hereinafter more fully set forth.

The novel features of my invention will 35 hereinabove be definitely claimed.

35 In order that my invention may be the better understood, I will now proceed to describe the same with reference to the accompanying drawings, wherein is illustrated a view partly in section and partly in elevation 40 of a feeding device constructed in accordance with my invention.

As disclosed in the accompanying drawings, T denotes a tank or receptacle divided at a desired point intermediate its length 45 by the partition 1 into an upper compartment A and a lower compartment B. The central portion of the partition 1 is provided with an opening 2 through which is directed a tubular casting C. The upper 50 portion of the casting C is in threaded engagement with the wall of the partition 1 defining the opening 2 and said open portion of the casting C is provided with an outstanding annular flange 3 overlying the upper 55 portion or face of the partition 1.

Interposed between said partition 1 and the flange 3 is a gasket 4 preferably of cop-

per. The lower portion of the casting C is provided at one side with a substantially flat face vertically disposed and the bore 60 5 through the casting is angular with its lower end opening through said flat face of the casting.

The bore 5 of the casting C affords communication between the upper compartment 65 A and the lower compartment B and coacting with the lower or discharge end of the bore 5 is a check valve 6, preferably a flap valve. The valve 6 is arranged within the compartment B so that said valve assumes 70 a closed position upon the creation of a vacuum or suction within the upper compartment A.

The body portion of the tank T comprises a cylindrical shell 7 and engaged with the 75 upper end portion of said shell is a ring 8 having its upper edge defined by an inwardly directed annular flange 9 partially overlying the top of the shell 7. The top of the shell 7 is closed by the head H, preferably a casting of white metal, and the marginal portion of said head H is secured to the inwardly directed flange 9 of the ring 8 by the screws 10 or the like.

The central portion of the head H has 85 disposed therethrough a port 11 having in communication therewith an L-joint 12 adapted to be interposed in a connection with the intake manifold of an internal combustion engine whereby a partial vacuum 90 may be produced in the upper compartment A. Engaged within the inner or lower portion of the port 11 is fitted a valve seat 14 with which coacts a valve 15 preferably of brass.

The valve 15 is mounted upon the upper 95 end portion of a vertically disposed guide rod or stem 16, the portion of said rod or stem 16 above the valve 15 extending within the lower portion of the port 11. The opposite or lower end portion of the rod or stem 16 extends within an upstanding sleeve 17 having its lower portion seated within the upper portion of the bore 5 of the casting C and forming a continuation of said bore. 105

The lower end portion of the rod or stem 16 is surrounded by and has secured thereto a flat disk 18 which contacts with the upper end of the sleeves 17 for limiting the downward movement of the stem or rod 16 and at 110 which time the valve 15 is in open position. 19 denotes a second disk surrounding the stem or rod 16 and carried thereby at a point between the valve 15 and the disk 18.

F denotes a float, preferably an annular hollow body, provided with a central opening 20 through which the rod or stem 16 is loosely directed and said float F is positioned between the disks 18 and 19 hereinbefore referred to.

The top or upper head H of the tank adjacent the margin thereof is provided with an inlet port 21 having in communication therewith an L-joint 22 held in applied position through the instrumentality of the reducing bushing 23 threaded in the upper portion of the inlet port 21. The upper or outer end portion of the reducing bushing 23 is defined by an outstanding flange 24 and interposed between said flange 24 and the adjacent face of the head H is a gasket 25, preferably of copper. Intersecting the port 21 and maintained therein by the bushing 23 is a strainer 26. The joint 22 is adapted to be interposed in connection with a suitable source of fuel supply.

The upper or top head H of the tank T is also provided with a second port or opening 27 normally closed by the plug P and which port or opening 27 permits priming of the tank T in the event the same should become dry. Extending axially of the plug P from the inner or inserted end thereof is a bore or recess 28 terminating adjacent the outer end of the plug P. In communication with the inner end of said bore or recess 28 is a restricted port 29 in communication with the atmosphere for a purpose which will be hereinafter more particularly referred to.

In communication with the lower compartment B is an air inlet pipe or vent 30 and which pipe or vent extends vertically through the compartment A adjacent a side thereof and extends exteriorly of the tank T through the top or upper head H.

The bottom or lower head L of the tank T is preferably concavo-convex and the lowermost portion thereof is provided with an opening 31 defined by a depending sleeve 32 in which is engaged a union 33 adapted for coaction with a line leading to the carbureter.

When the float F rests upon the disk 18, the weight of the float F moves the valve or stem 16 downwardly, bringing the valve 15 into an open position. This results in the formation within the compartment A of a partial vacuum and the valve 6 closes. As the liquid fuel level within the compartment A rises, as the fuel is delivered therein, the float F also rises and said float contacts with the disk or stop 19 and moves the stem or rod 16 upwardly and the valve 15 into closed position. At this time, the valve 6 will open under the influence of the weight of the fuel within the compartment A and discharge within the lower compartment B.

The port 29 in the plug P is so restricted that the air admitted within the compartment A through such port does not interfere with the requisite feeding of the fuel but when the valve 15 is closed, this restricted port 29 permits admission of sufficient air to facilitate the relieving of the vacuum in the compartment A so that the feeding operation is effected with greater speed.

The sleeve 17 terminates a desired distance above the partition 1 and provides an effective means to prevent water or sediment from flowing into the lower compartment B. This provision is not a disadvantage because in cleaning out devices of this general character, it is necessary to wipe the water and sediment out with a cloth so that with the use of the sleeve 17, the bottom or lower head L may be made simple in form or construction.

From the foregoing description it is thought to be obvious that a feeding device for liquid fuel constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

A device of the character described comprising vertically spaced compartments having an intercommunicating port, the upper compartment being provided with a fuel inlet and with a vacuum connection, the lower compartment being in communication with the atmosphere above the liquid level therein and also having a discharge in its lower portion, a vertically movable stem within the upper compartment provided with a valve for controlling the vacuum connection, said stem being provided with longitudinally spaced stops, a float within the upper compartment and coacting with the stops carried by the stem, said float being positioned between said stops, a check valve for closing the intercommunicating port of the compartments, such check valve closing upon the creation of a partial vacuum within the upper compartment, and a sleeve arranged in the upper compartment, said sleeve being a substantial continuity of the intercommunicating port and terminating above the bottom of the upper compartment, the lower stop of the stem contacting with the upper end of the sleeve for limiting the opening movement of the valve.

In testimony whereof I hereunto affix my signature.

RUSSELL C. HUFF.
